United States Patent

Des. 239,418

Patented Mar. 30, 1976

239,418

WEARABLE PURSE

Roger Bowman, Medford, N.J., assignor to Aggogle Inc.

Filed Dec. 10, 1973, Ser. No. 423,162

Term of patent 14 years

Int. Cl. D3—01

U.S. Cl. D87—1 R

FIG. 1 is a plan view of the rear face of a wearable purse in accordance with the invention;

FIG. 2 is a plan view of the front face thereof;

FIG. 3 is a side elevational view thereof;

FIG. 4 is an end elevational view thereof; and

FIG. 5 is a perspective view thereof, the broken line showing of an arm being for purposes of illustration only.

I claim:

The ornamental design for a wearable purse, substantially as shown and described.
